GARMENT HANGER

Alfred C. Schoepfer, St. Petersburg, Fla.

Application February 21, 1947, Serial No. 729,965

6 Claims. (Cl. 223—96)

1

This invention relates to garment hangers, the object being to provide a new and improved character and relationship of parts which includes two like members hinged one to the other and between which a garment may be supported, provision being made for the supporting of garments of greater or less thickness.

My improved garment hanger is shown in the accompanying drawing in which—

Fig. 1 is a perspective view of my improved garment hanger.

Fig. 2 is a view taken from the right hand end of Fig. 1.

Fig. 3 is a cross section taken on line 3—3 of Fig. 1.

Fig. 4 is an end view showing the relationship of parts when in the open position.

Fig. 5 shows an alternative form of chain.

The garment hanger, according to my invention, includes the two strips 1 and 2 preferably of the same form and outline and at each end of the strip 2 is a metal pin 3 terminating in an eyed portion 4 and at each end of the strip 1 is a pin 5 having an inturned end portion 6 engaged in the eyes of the respective pins 3 and function after the manner of a hinge. The pins 3 and 5 are attached to the respective strips 1 and 2 and extend to below the strips and one of the pins has an eyed end portion and the other pin has a terminal portion at a right angle to the body thereof which extends into the eye of the pin 3. It is to be noted that by this arrangement of parts the pads 1a and 2a are under greater pressure at the lower edge than at the upper edge which is of material value in that the hinge point is below the lower edge of the strips 1 and 2 and when the strips are clamped together the pressure on the garment is greater at the lower edge than at the upper edge of the strips. The trousers therefore would have to pull through the smaller space before they could be dislodged by gravity or by strain applied as by pulling on the trousers. If the tension was greater at the upper edge of the strips than at the lower edge the garment could readily be pulled out as the pressure on the lower edge of the strips 1a and 2a would be less than the pressure at the upper edge. The strips 1 and 2 may be of any approved material but are preferably formed of wood and on the inner face of the strip 1 is a pad 1a adjacent each of its opposite ends and on the strip 2 is a pad 2a at each of its opposite ends. A hook 7 preferably formed of wire has a terminal end secured centrally between the ends of the strip 1 and a chain 8 has an eyed end link 9 through which the stem 7a of the hook element extends.

The chain 8 is formed of ball like portions 10 connected by wire like portions 10a and a plate 11 is secured to the strip 2 as by means of the screws 12. The upper outturned edge 13 of the

2

plate is formed with a notch 14 into which the wire portion 10a of the chain may be inserted and is of less width than the diameter of the balls. This arrangement permits variation in spacing of the bars 1 and 2 depending upon the thickness of the material placed between the bars. The free end of the chain is provided with an eyed link 15 and a ball 16 has a pin 17 provided with a looped end 18 engaging in the eye of the link 15 forming the terminal of the chain 8 which is a well known product.

It will be evident from Fig. 4 that the bars 1 and 2 may be varied in spacing as hereinbefore described. This arrangement permits adjustment in the spacing of the bars 1 and 2 to accommodate greater or less thickness of material to be clamped between the bars.

While I have shown the pads 1a and 2a being of short length and respectively located adjacent each of the opposite ends of the bars 1 and 2 they may be of greater length extending practically the full length of the bars without departing from the spirit and scope of the invention herein disclosed.

Furthermore, the chain may be formed of links 18a of sheet material connected by links 19 of like character as suggested in Fig. 5. The intermediate link 19 may engage in the slot in the plate 11 which has its upper edge outturned as indicated at 13.

From the foregoing description taken in conjunction with the drawing it is believed obvious that the device is comparatively simple and inexpensive in construction and that various changes may be made in the form and relationship of parts without departing from the spirit and scope of the invention as herein disclosed.

Having thus briefly described my invention, its utility and mode of operation, what I claim and desire to secure by Letters Patent of the United States is:

1. A garment hanger comprising a pair of horizontal spaced strips, hinges depending from the lower longitudinal edges of said strips at opposite ends thereof, an upright inverted hook connected centrally to one of said strips, a plate secured centrally on the outer surface of the other strip and projecting above its top edge, and having a central notch in its projecting portion, and a chain including a series of spaced elements anchored to said one strip with intermediate elements thereof adapted for selective registry relative to said notch for clamping the strips together to hold a garment therebetween, said hinge arrangement defining an upright V-shaped opening between said strips and the joint of the hinge for increased tension between their lower edges.

2. A garment hanger comprising a pair of horizontal spaced strips, hinges depending from the

lower longitudinal edges of said strips at opposite ends thereof, an upright inverted hook connected centrally to one of said strips, a plate secured centrally on the outer surface of the other strip and projecting above its top edge, and having a central notch in its projecting portion, and a chain including a series of spaced elements anchored to said one strip with intermediate elements thereof adapted for selective registry relative to said notch for clamping the strips together to hold a garment therebetween, said hinge arrangement defining an upright V-shaped opening between said strips and the joint of the hinge for increased tension between their lower edges, each hinge comprising pins depending from adjacent ends of each strip, and means pivotally joining the lower ends of said pins.

3. A garment hanger comprising a pair of horizontal spaced strips, hinges depending from the lower longitudinal edges of said strips at opposite ends thereof, an upright inverted hook connected centrally to one of said strips, a plate secured centrally on the outer surface of the other strip and projecting above its top edge, and having a central notch in its projecting portion, and a chain including a series of spaced elements anchored to said one strip with intermediate elements thereof adapted for selective registry relative to said notch for clamping the strips together to hold a garment therebetween, said hinge arrangement defining an upright V-shaped opening between said strips and the joint of the hinge for increased tension between their lower edges, each hinge comprising pins depending from opposite ends of one strip having an eye at their lower ends, and a second pin depending from adjacent ends of the other strip having inturned portions at their lower ends pivotally projected and retainingly engaged within said eyes.

4. A garment hanger comprising a pair of horizontal spaced strips, hinges depending from the lower longitudinal edges of said strips at opposite ends thereof, an upright inverted hook connected centrally to one of said strips, a plate secured centrally on the outer surface of the other strip and projecting above its top edge, and having a central notch in its projecting portion, and a chain including a series of spaced elements anchored to the lower end of said hook with intermediate elements thereof adapted for selective

registry relative to said notch for clamping the strips together to hold a garment therebetween, said hinge arrangement defining an upright V-shaped opening between said strips and the joint of the hinge for increased tension between their lower edges.

5. A garment hanger comprising a pair of horizontal spaced strips, hinges depending from the lower longitudinal edges of said strips at opposite ends thereof, an upright inverted hook connected centrally to one of said strips, a plate secured centrally on the outer surface of the other strip and projecting above its top edge, and having a central notch in its projecting portion, a chain including a series of spaced elements anchored to said one strip with intermediate elements thereof adapted for selective registry relative to said notch for clamping the strips together to hold a garment therebetween, said hinge arrangement defining an upright V-shaped opening between said strips and the joint of the hinge for increased tension between their lower edges, and pads upon the inner opposed faces of each of said strips adjacent their outer ends.

10 6. A garment hanger comprising a pair of horizontally arranged spaced strips hingedly connected at their ends along their lower longitudinal edges, a hook centrally connected to one of said strips, a plate secured centrally upon the outer surface of the other strip and projecting above its top edge and having a central notch in its projecting portion, and a chain anchored to the lower end of said hook with intermediate portions thereof selectively positioned and secured within 15 30 35 said notch.
